Inventor:
Franck P. Woodcock

UNITED STATES PATENT OFFICE.

FRANK P. WOODCOCK, OF NEW YORK, N. Y.

IMPROVED PACK-SADDLE.

Specification forming part of Letters Patent No. 40,533, dated November 8, 1863.

To all whom it may concern:

Be it known that I, FRANK P. WOODCOCK, of New York, in the county and State of New York, have invented a new and useful Improvement in Pack-Saddles; and I do hereby declare that the following is a full and exact description thereof, reference being had to the accompanying drawing, and to the letters of reference marked thereon.

The nature of my invention consists in the arrangement and combination of projecting bars or posts with the pommel and cantle of a saddle, from which the bearing-bars or frame-work, which receive the load or burden, are suspended, and provided with suitable braces, whereby the strain of the weight is brought near to the center of the saddle-tree; and, further, in the arrangement of suitable pads or cushions on the saddle-flaps to relieve the horse's belly from the side pressure of the load.

In the accompanying drawing, a perspective view of my improved pack-saddle is shown, where A represents the saddle-tree; B, the pommel; C, the cantle; D D, the saddle-flaps; E E, the saddle-girts, and N the Mexican girt-rigging, constructed in the usual manner. F F are bars or posts attached to the pommel B and cantle C, and made of such a length as to bring the suspended load or burden clear of the horse's belly.

On the top of these posts F straps a are fastened, passing through suitable rings, n n, or their equivalent, attached on the top to the center of the pommel B and cantle C, and passing then back again over the top of said posts downward. The ends of these straps a are provided with suitable hooks p, to which the outward ends of the straps m of the bearing-bars G are attached. By this arrangement of the straps a the same act so as to support the load or burden placed upon the bars G, and act at the same time as braces for the posts F in such a manner as to bring the weight or strain of the burden to the center of the saddle-tree. Instead of arranging these straps a as here described, the strap from which the load is suspended may be attached to the upper end of the posts F, and a brace-strap arranged passing from the top of the post to the ring or hook fastened at the center of the pommel and cantle.

H H are guide straps, fastened to the top of the posts F and provided at their lower ends with hooks v, to which the straps s on the forward and after ends of the bearing-bars G are attached, whereby any swinging motion of the head is prevented.

w and w' are hooks, attached to the sides of the saddle or to the saddle-girts, to which the inward ends of the straps m of the bearing-bars G are attached.

G G are the bearing-bars or frames, fastened together by the straps s s m m, upon which the load or burden to be carried is placed.

M M are pads, secured to the saddle-flaps D, to relieve the horse's belly as much as possible from the pressure of the burden.

The inner sides of the bearing-bar straps m are attached, as above described, to the hooks w or w', according as the weight is intended to be carried higher or lower, while the outer ends of said straps m are supported by the straps a. The weight of the load placed upon the bearing-bars G will be carried over the posts F and brought upon the center of the saddle-tree, while the pads M will relieve the horse's belly from the side pressure.

The straps a and H are made in two parts, and provided with suitable buckles to lengthen or shorten the same, as may be required. Instead of straps, as above described, ropes or chains may be used, capable of being lengthened or shortened.

What I claim as my invention, and desire to secure by Letters Patent, is—

1. The herein-described manner of suspending burdens from a pack-saddle, substantially as set forth.

2. The arrangement of the posts F, attached to the pommel and cantle of a pack-saddle, in combination with the straps a, to support the load or burden, and the manner of bracing said posts so as to bring the strain of the weight near the center of the saddle-tree, as described.

3. The forward and after guide-straps, H, for the purpose specified.

4. In combination with the above arrangement, the pads M, for the purpose described and set forth.

FRANK P. WOODCOCK.
